HANDLE FOR AN ORTHOPEDIC CANE

William J. Kurpis, 4342 S. Paulina St.,
Chicago, Ill. 60609

Filed May 16, 1966, Ser. No. 2,301

Term of patent 14 years

(Cl. D88—4)

FIGURE 1 is a perspective view of a handle for an orthopedic cane showing my design;

FIGURE 2 is a side elevational view thereof on a reduced scale; and

FIGURE 3 is an end elevational view as seen on lines 3—3 of FIGURE 2 on a slightly larger scale;

FIGURE 4 is a top plan view thereof on a reduced scale.

The broken line showing of a cane or portions thereof in FIGURES 1-3 is for illustrative purposes only.

I claim:

The ornamental design for a handle for an orthopedic cane, as shown and described.
